UNITED STATES PATENT OFFICE.

CHESTER S. RICKER, OF INDIANAPOLIS, INDIANA.

AIR-COOLED CYLINDER.

Application filed February 9, 1920. Serial No. 357,171.

To all whom it may concern:

Be it known that I, CHESTER S. RICKER, a citizen of the United States, residing at Indianapolis, in the county of Marion and State of Indiana, have invented a new and useful Air-Cooled Cylinder, of which the following is a specification.

It is the object of my invention to cool internal combustion engines by air, by a construction which is simple and inexpensive and an arrangement which provides an efficient air movement.

The accompanying drawings illustrate my invention. Fig. 1 is a transverse section through an engine cylinder provided with my improved air cooling structure, being taken on the line 1—1 of Fig. 2; Fig. 2 is a part elevation and part longitudinal section on the line 2—2 of Fig. 1 of such engine cylinder; Fig. 3 is an end elevation, in partial section, of a fixed radial type engine embodying my invention; and Fig. 4 is a bottom plan of the engine shown in Fig. 3, with the fan in section.

Referring first to Figs. 1 and 2, in which a single cylinder is shown, the cylinder 10 is of any desired type, with any suitable valve arrangement for its intake and exhaust. In the outer surface of the cylinder 30 are embedded a plurality of thin metal members 11, which are approximately L-shaped in cross section, as is clear from Fig. 1. These members project radially from the cylinder, and the free end of the base 35 of the L of each abuts against the heel of its neighbor. The members 11 form a complete circumferential series of longitudinal air passages 12, each of which is formed by two adjacent L-shaped members, the base 40 of one of such members, and the cylinder wall itself. This is a construction which is very easily manufactured, as the L-shaped members may be made of rolled sheet metal or of sheet-metal stampings and can readily 45 be firmly embedded in place in the outer surface of the cylinder.

The passages 12 are open at their ends, and air may be caused to flow through them in various ways. A preferred arrangement 50 for producing this flow of air in radial type

engines is shown in Figs. 3 and 4. The several cylinders 10 are arranged radially around a common crank shaft 13, in the usual manner of radial type engines, so that the passages 12 are radial with respect to the complete engine. The outer ends of the 55 passages 12 are open to the atmosphere. The inner ends of such passages 12 open into a chamber 14 surrounding the crank case 15 in which the shaft 13 is located, 60 which chamber 14 is common to the passages 12 of all the cylinders. This chamber 14 is closed at one axial end, by an end wall 16, and at the other axial end opens 65 into the central intake eye of a centrifugal fan 17 concentric with the shaft 13, which shaft carries the blades of the fan. As the shaft 13 rotates, the centrifugal fan throws air outwardly through the openings 18 in its periphery, thus creating a suction which 70 causes a continuous inflow of air through the passages 12 into the chamber 14. This produces a flow of air which effectively cools 75 the cylinders.

I claim as my invention:

1. A cylinder for internal combustion engines having continuous longitudinal heat radiating fins, each fin having at its outer edge a flange extending to the next fin, such fins with their flanges forming a plurality 80 of longitudinal air passages open at top and bottom for permitting air to be passed lengthwise of the cylinder past the fins within the casing formed by the fin-flanges.

2. A cylinder for internal combustion engines having continuous longitudinal heat radiating fins embedded in the cylinder wall, each fin having at its outer edge a flange extending to the next fin, such fins with their flanges forming a plurality of 85 longitudinal air passages open at top and bottom for permitting air to be passed lengthwise of the cylinder past the fins within the casing formed by the fin-flanges.

In witness whereof, I have hereunto set 90 my hand at Indianapolis, Indiana, this fifth day of February, A. D. one thousand nine hundred and twenty.

CHESTER S. RICKER.
